(57) **CLAIM**

We claim the ornamental design for a topload washing appliance, as shown and described.

DESCRIPTION

FIG. 1 is a first top perspective view of the topload washing appliance of the present invention;

FIG. 2 is a second top perspective view of the topload washing appliance of the present invention;

FIG. 3 is a top plan view of the topload washing appliance of the present invention;

FIG. 4 is a bottom plan view of the topload washing appliance of the present invention;

FIG. 5 is a first side elevation view of the topload washing appliance of the present invention;

FIG. 6 is a second side elevation view of the topload washing appliance of the present invention;

FIG. 7 is a third side elevation view of the topload washing appliance of the present invention;

FIG. 8 is a fourth side elevation view of the topload washing appliance of the present invention;

FIG. 9 is another first side elevation view of the topload washing appliance of the present invention with the door in an open position to view the underside of the washing appliance door;

FIG. 10 is a first top perspective view of the topload washing appliance of an alternative embodiment of the present invention;

FIG. 11 is a second top perspective view of the topload washing appliance of an alternative embodiment of the present invention;

FIG. 12 is a top plan view of the topload washing appliance of an alternative embodiment of the present invention;

FIG. 13 is a bottom plan view of the topload washing appliance of an alternative embodiment of the present invention;

FIG. 14 is a first side elevation view of the topload washing appliance of an alternative embodiment of the present invention;

FIG. 15 is a second side elevation view of the topload washing appliance of an alternative embodiment of the present invention;

FIG. 16 is a third side elevation view of the topload washing appliance of an alternative embodiment of the present invention;

FIG. 17 is a fourth side elevation view of the topload washing appliance of an alternative embodiment of the present invention; and,

FIG. 18 is another first side elevation view of the topload washing appliance of an alternative embodiment of the present invention with the door in an open position to view the underside of the washing appliance door.

The broken lines shown in the drawings are included for the purpose of illustrating environmental structure and form no part of the claimed design.

1 Claim, 18 Drawing Sheets
